CLAIM

The ornamental design for an egg carton, as shown and described.

DESCRIPTION

FIG. 1 is a front perspective view from above of the invention;

FIG. 2 is a back perspective view from above of the invention;

FIG. 3 is a back perspective view from below of the invention;

FIG. 4 is a back side view of the invention;

FIG. 5 is an end view of the invention; and,

FIG. 6 is a top view of the invention.

The broken line showing in the drawings of internal features illustrates portions of the egg carton that form no part of the claimed design.

1 Claim, 5 Drawing Sheets
